EUGÈNE BRANDT, OF GENEVA, SWITZERLAND

NUT LOCKING DEVICE

Application filed July 10, 1929, Serial No. 377,285, and in Switzerland March 15, 1929.

This invention relates to nut locking devices adapted to lock at least two nuts. Devices of this type are known which comprise a plate arranged to be clamped between the nuts and their support and in which two tongues are cut which are adapted to act upon the nuts after the manner of pawls.

Experience has shown that in order that the tongues may possess sufficient elasticity, the plate should be made of steel, and in order to permit the tongues to be cut out with ease, this plate should be fairly thin. But under these circumstances, the plate is no longer capable of withstanding the mechanical stresses to which it is subjected, particularly when the device is employed upon the fish plates of railway tracks.

The subject of the present invention is a locking device for at least two nuts, characterized by the feature that it is formed by an elastic rod so shaped as to pass beneath the nuts and such that its raised ends each press elastically upon the periphery of one of the nuts in a direction tangential to this periphery.

As the operation of bending a rod of steel is more easy to effect than cutting out, steel rods of sufficient strength to withstand all the stresses may be chosen, for example rods of square section with the dimensions of the faces varying from 7 to 10 m/m.

In this way the above mentioned disadvantage is removed while the manufacture is simplified.

The accompanying drawings illustrate by way of example five forms of construction of the subject of the invention as applied to the fish plates of railway tracks.

Fig. 1 is a plan view, and

Fig. 2 an elevation of the first form of construction.

Fig. 3 shows the latter in perspective view.

Fig. 4 is a plan view of the second form of construction.

Fig. 5 is a plan view of the third form of construction.

Fig. 6 is a plan and

Fig. 7 an elevation of the fourth form of construction.

Fig. 8 is a plan view and

Fig. 9 an elevation of the fifth form of construction.

The form of construction shown in Figs. 1 and 2 is formed of a steel rod 1 of square cross section, the dimensions of each side being 8 mm. (This cross section may also adopt a different shape, for example circular). The central part of this rod situated between the two bolts *a* comprises at its centre a bridge 2. Each of the end parts of this rod, after having passed round the corresponding bolt *a*, under a nut *b*, passes beneath this bridge 2, and returns towards its nut, at the same time rising gradually in such a way that its end 3 is situated at the height of this nut, in a direction which is tangential to the periphery of the latter, and presses elastically against this periphery.

A triangular lodgment 4 formed in this end permits the latter to press both against the edge of the nut, (see to the right of Fig. 1) and on a face of the latter (see to the left in Fig. 1).

Before being introduced beneath the two nuts *b*, the device is not flat, but slightly curved in the longitudinal direction, so that the loops which are intended to surround the bolts are higher than the central part of the device (see Fig. 3) by an amount *h* equal to 4 mm. about. When the nuts are completely screwed down, they depress the loops which react elastically upon the nuts, thus permitting wear to be taken up.

Naturally this device may also be flat before being introduced beneath the nuts. In this case the bridge 2 may be dispensed with, the chief function of this bridge being to prevent the end 3 from rising when the corresponding loop is flattened by its nut.

When one of the branches is situated below one of the nuts, as is the case in the embodiment shown in Figs. 1 to 3 before the nuts are tightened, it frequently happens that it is damaged by the wrench with which the nut is tightened. The embodiments according to Figs. 4 and 5 in which the two branches are above the nut, remove this disadvantage.

In the form of construction shown in Fig. 4, the rod 1 is gripped by two bolts which it surrounds. Its end 9, after having passed

beneath the right hand nut, presses against the periphery of the left hand nut and the end 8 clamped by the left hand nut presses against the right hand nut while passing 5 above the branch 9.

In the form shown in Fig. 5, the rod 1 surrounds the two bolts. From here the branch which has passed beneath the right hand nut will press upon the periphery of 10 the left hand nut and the end 10 which passes from the left hand nut passes round the right hand nut and then presses upon its periphery at its upper part.

In the form of construction shown in Figs. 15 6 and 7, each half of the rod 1 passes beneath a nut. From here the branches 11 and 12 form two loops 13 and rise gradually in order to press elastically upon the central 20 part of their nut.

20 This device is not flat before being gripped by the nuts but the loops 14 are slightly curved in a longitudinal direction, the top of the curvature being raised out of the vertical plane of the rod by an amount h equal to 25 3 mm. about (see Fig. 7). When the nuts are completely screwed down, they depress the two curved loops 14 which react elastically upon the nuts, thus permitting wear to be taken up. When the two nuts are tightened the 30 loops 14 of the device flatten out and the two ends 11 and 12 are not moved. As these two ends are upwardly curved it is not necessary to provide a bridge as in the embodiment 35 shown in Figs. 1 to 3.

35 In the embodiment according to Figs. 8 and 9 the rod 1 having passed below the nuts forms two loops 15 and 16, one loop being disposed above the other one. The end 17 of the 40 rod, after passing below the loop 15, is upwardly curved so as to come in touch with the side of the nut. This device has the advantage that it can be used for such bolt connections where the distance between the axis of two 45 adjacent bolts a is not always the same as will be the case with the railroad fish plate 50 connections in the various countries. The device can be shortened or lengthened while the two loops 15 and 16 can slide above each other.

50 I claim:—

1. A device for locking nuts on their bolts, comprising a single resilient rod having a central portion extending between two bolts and forming two bolt embracing loops beneath the nuts, the portion of the rod extending between the two bolts forming a bridge, each end portion of the rod extending from the loop beneath the nut to the free end of the rod passing beneath the bridge 55 and then returning towards the said nut and being raised to resiliently engage the sides and corners of the nut.

2. A device for locking nuts on their bolts, comprising a single resilient rod having a 60 central portion extending between two bolts

and forming two bolt embracing loops beneath the nuts, and having two end portions extending from the loops to the free ends of the rod and being raised with respect to the central portion, each raised end portion 70 extending from the loop towards one of the nuts and both ending on the same side relative to the longitudinal axis of the device passing through the two loop centers to provide resilient pressure against the sides and 75 corners of the nuts on corresponding sides of the two nuts.

In testimony whereof I affix my signature.

EUGÈNE BRANDT.
